AIR RAID BLACK-OUT BOX

Eugene Van Damme, Richmond Hill, N. Y., by
judicial change of name Eugene Vannee

Application February 11, 1942, Serial No. 430,344

7 Claims. (Cl. 200—168)

This invention relates to new and useful improvements in an air raid black-out box for stores, offices and other establishments, and an emergency break-glass device to give alarms and for other purposes.

Under existing war conditions many cities and towns have emergency laws requiring that owners of stores, offices and similar business places extinguish all lights when leaving the premises to meet the requirements of blackouts and air raids, thus leaving the premises in total darkness and making it easy for unauthorized persons to break into the premises.

The invention proposes the construction of a novel black-out box adapted to be mounted on an outside wall of a store or other business place, and which is connected in an electrical circuit including store window lights, neon signs, internal lights, and any other lights which may be left burning when leaving the premises.

A further object of the invention proposes to provide the box with a fragile stiff sheet which may be easily broken and which controls an electrical switch or switches arranged in a manner to open a circuit which includes the window lights, neon signs and other internal lights, to cause these lights to be quickly put out when the fragile sheet is broken, or depending on the design to close circuits for giving an alarm or for other purposes.

Still further the invention proposes to mount these boxes within easy reach of air wardens, or policemen patrolling a given area to permit these persons or other persons to quickly extinguish all lights or give an alarm in their particular vicinity by merely visiting the boxes and breaking the fragile sheets.

A further object of the invention proposes the construction of a circuit breaker which merely requires the replacement of the fragile sheet for again illuminating the lights after the black-out, air raid or danger period has passed or the emergency without the use of any tools.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view illustrating the application of an air raid black-out box constructed in accordance with this invention.

Fig. 2 is a front elevational view of the box, per se.

Fig. 3 is a vertical sectional view taken on the line 3—3 of Fig. 2.

Fig. 4 is a horizontal sectional view taken on the line 4—4 of Fig. 2.

Fig. 5 is a perspective view of the container holding the spare fragile sheets.

Fig. 6 is a perspective view of the box used for catching the broken pieces of glass.

Fig. 7 is a fragmentary enlarged detailed view of a portion of Fig. 2 showing particularly the lower left hand corner of the window opening.

Fig. 8 is a schematic wiring diagram of the device.

Fig. 9 is a horizontal sectional view similar to Fig. 4 but illustrating a modified construction.

The air raid black-out box for stores, offices and other places, according to this invention, includes

20 a box 10 which is adapted to be mounted on the outside wall of a business establishment in a manner to be readily accessible to air raid wardens, policemen and others patrolling a given area. The box 10 comprises a body portion 11 securely mounted upon the said outside wall and having a front opening closed by means of a cover 12. The cover 12 is pivotally supported upon hinges 13 and is provided with a substantially centrally located window opening 14. The cover 12 is further provided with an inside snap-catch 15 engageable with a complementary keeper 16 mounted upon an adjacent portion of the body 11 for locking and maintaining the cover in a closed position. A grooved or groove-like strip 17 having a laterally offset bottom portion is securely welded or attached to the inside face of the cover 12 immediately adjacent the top edge of the window opening 14.

40 A movably mounted lever 19 is located within the interior of the box 10. The lever 19 is constructed of suitable material, such as a piece of sheet metal, and has at its rear edge laterally directed tongues 20 which freely engage into eye members 21 mounted on the rear of the box 10. The inter-engagement of the tongues 20 and eye members 21 act to pivotally support the lever 19, permitting its front edge to move freely upwards and downwards.

45 The free front edge of the lever 19 is normally disposed at a side of the window opening 14 particularly that side which is opposed to the side having the strip 17. The lever 19 is formed with a groove 22 which extends downwards thereof and which in a certain pivoted position of the

lever 19 falls immediately below the groove-like space of said strip 17.

A switch member 23 is mounted on the back wall of the box 10. This switch member 23 is secured in position by means of bolts 24 which are attached on the box 10. The switch 23 has a depressible plunger 25 which extends upwards and bears against the bottom face of the lever 19. The plunger 25 is resiliently urged into a raised position and normally tends to urge the lever 19 towards the strip 17. The switch 23 is of the type which assumes a normal closed position when the plunger 25 is depressed and which automatically opens when the plunger 25 is free to move upwards.

A fragile stiff sheet 27 such as a pane of glass is extended across the window opening 14 and has its top edge engaging the groove-like space of strip 17 and its bottom edge engages the groove 22 in the lever 19. The fragile sheet 27 normally acts to hold the lever 19 in a position in which the plunger 25 will be depressed to maintain the switch 23 in a closed position. However, it is possible to shatter the fragile sheet 27 with a stone, coin or other article to be urged upwards by the plunger 25 to open the switch 23.

Mounted within the box 10 and upon one wall thereof immediately to the rear of the window opening 14 there is a signal lamp 28 which remains lit during the time the switch 23 is closed for the purpose of indicating to passing air raid wardens and patrolmen and others that the circuit is in operation and all lights controlled thereby are lit.

The switch 23, the signal lamp 28, and the light or lights 29 of the establishment are connected together in series in an electrical circuit 30 including a source of power for causing the light or lights 29 of the establishment and the signal lamp 28 to be lit when the switch 23 is closed. This circuit 30 also includes a two way switch 31 which is mounted upon an inside wall of the establishment and which is adapted to be controlled by a person working therein. This switch 31 is provided for the purpose of opening the circuit 30 independently of the switch 23 during the day and during such other periods when it is desired to have these lights out. The switch 31 is so arranged that it is possible to have the light or lights 29 lit without the signal lamp 28 being lit. The operation of this switch 31 is controlled by a manually rotatable knob 32. This switch 31 also has a position in which all of the lamps are out.

On the drawings the lamp 29 is provided merely for illustrative purposes. Other lights, neon lights, window lights or any other similar lights which might be normally left illuminated during the night may be controlled by this box, by means of an additional switch or switches installed alongside of switch 23 (not in series with lamp 28).

It is noted that the front edge of the lever 19 is provided with a downwardly extended lip 33 which overlaps the bottom part of the window opening 14 allowing for play while installing glass and which prevents the cover 12 from being opened until such time as the fragile sheet 27 which holds the lever 19 down is broken. This acts to prevent unauthorized persons from meddling with the system and is so arranged as to free the cover to be opened when the fragile sheet 27 is removed by authorized persons. Located at a position beneath the switch 23 and within the

box 10, there is provided a container 34 which encases a plurality of auxiliary fragile sheets 27' which are adapted to be engaged in the window opening 14 when the fragile sheets 27 are broken.

5 The lever 19 has an upwardly bent portion 19^a directly behind the groove 22 forming an abutment for the pane 27. This abutment projects above the top face of the lever. It is useful in guiding the pane 27 into the groove 22. The 10 lower edge of the pane 27 need only be pushed rearwards on the top face of the lever 19 until it reaches the abutment 19^a and then the lever 19 is free to move upwards so that the groove 22 engages the bottom edge of the pane 27.

15 The bottom corners of the window 14 are provided with small upwardly directed lugs 14^a and 14^b adapted to engage the back and front faces of the bottom corners of the pane 27 for supporting the pane. Along the sides the window opening 14 is provided with inwardly offset flanges 14^c against which the pane 27 may rest.

20 A small auxiliary box 37 with an open top is mounted in the bottom portion of the box 10 and is adapted to catch the particles of the pane 27 25 when the latter is shattered. The lever 19 has a large cutout portion 38 through which the shattered pane 27 may fall so as to be caught by the box 37. The back wall of the box 37 is formed with a cutout 39 which accommodates the bolts 30 24 which support the switch 23. The box 10 is also formed with louvres 40 at its sides through which the heat given off by the lamp 28 may readily pass. The auxiliary box 37 is formed with a drain opening 41, and the bottom of the box 35 10 is also formed with one or more drain openings 42 so that if any water collects in the box it may be drawn off.

30 In Fig. 9 a modified form of the invention has been disclosed which distinguishes from the prior 40 form in the fact that several additional switches, besides the switch 23 are mounted within the box 10. As shown in Fig. 9 there are three switches in all. The additional switches are indicated by reference numerals 45 and 46. These 45 switches are also supported by bolts 24 upon the back wall of the box 10. Each of these additional switches is provided with depressible plungers 25 which are held in a depressed condition 50 when the lever 19 is in its operative position against the bottom edge of the pane 27. The switches 45 and 46 may be of the same type as the switch 23, that is, they are closed when their plungers 25 are depressed, or they may be of the 55 type in which they are opened when their plungers 25 are depressed. This is merely a matter of design and depends upon what purpose the emergency device is to be used. If the device is used to give an alarm when the pane 27 is broken, one or more of the switches must close one or more 60 circuits, in the latter instant. The additional switches may be used for various purposes which will be readily understood from this specification.

65 The operation of the device is as follows: With the circuit 30 connected as illustrated in Fig. 8 a person leaving the premises at night turns the switch 31 to illuminate the lamp 29 and the signal lamp 28 located within the box 10 mounted upon an outside wall of the establishment. If during the night an air raid or black-out should take place a passing warden or policeman noting the illuminated box 10 breaks the fragile sheet 27, freeing the lever 19 and permitting the plunger 25 to move upwards to open 70 75 the switch 23 and break the circuit 30, extin-

guishing all of the lamps including the signal lamp 28. It thus becomes apparent that an air raid warden operating a given territory may quickly extinguish all of the lights in his immediate vicinity by merely walking the given area and breaking the fragile sheets 27.

By means of this device, a whole block of stores could be put in darkness by merely installing one such box at a centralized spot. Switch 23 controls a series of remote control switches, each of which would control an individual store. The power for this centralized box would be supplied by the premises upon which said box is installed and the cost of current is only that of light in said box and loss of flux in said system. Each store operates on its own current.

Application of an air blackout box, in accordance with this invention, permits the owners of stores to properly illuminate their premises to protect the same against burglary and provides a means whereby these lights may be quickly extinguished.

This invention also serves another useful purpose in that a policeman patrolling a given area during times when a blackout is not in progress, and seeing a store not illuminated will immediately become suspicious and investigate to frustrate attempted burglary.

After the fragile member 27 has been broken the circuit may again be completed by taking one of the auxiliary fragile members 27' from the container 34 and engaging the same in position between the groove strip 17 and the lever 19 in back of the window opening 14 for which no tools are necessary. It will be noted that the fragile sheets 27 are of a size slightly smaller than the height of the window opening 14 permitting them to be easily engaged into position through the window opening while the cover 12 is in a closed position, and the lever is in a horizontal position, and slightly larger in width than the recessed opening 14 so that the sides will rest against the lips of the opening 14.

It is to be understood that one of the most important features of this invention is the unique lever 19 arrangement which keeps the switch 23 in a normally closed position when the circuit is in operation and the glass sheet 27 is in position. Should the glass 27 be shattered the lever 19 will automatically open the circuit which is controlled by the switch 23.

This box, by eliminating the light socket 28 and installed with a switch, the opposite type of switch 23, namely a switch normally open, would thereby become ideally suited for use as a fire alarm, emergency break switch and all other emergency break glass type device for buildings, ships, trains, trolleys, buses, etc.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. Any device of the type described, a box having a window opening, a grooved strip mounted along one side of said window opening, a pivotally mounted lever within said box and extended to the other side of said window opening and having a groove opposed to said groove, a

switch for controlling an electric circuit and having a plunger resiliently urged outwards and engaging and urging said lever towards said grooved strip, said switch being normally closed when said plunger is depressed and open when said plunger is extended, and a fragile stiff sheet extended across said window and engaging in said grooves for holding said lever and said plunger depressed.

10 2. Any device of the type described, a box having a window opening, a grooved strip mounted along one side of said window opening, a pivotally mounted lever within said box and extended to the other side of said window opening and having a groove opposed to said groove, a switch for controlling an electric circuit and having a plunger resiliently urged outwards and engaging and urging said lever towards said grooved strip, said switch being normally closed when said plunger is depressed and open when said plunger is extended, and a fragile stiff sheet extended across said window and engaging in said grooves for holding said lever and said plunger depressed, said box having an open front side closed by means of a pivotally mounted cover, and said window opening being formed in said cover.

20 3. Any device of the type described, a box having a window opening, a grooved strip mounted along one side of said window opening, a pivotally mounted lever within said box and extended to the other side of said window opening and having a groove opposed to said groove, a switch for controlling an electric circuit and having a plunger resiliently urged outwards and engaging and urging said lever towards said grooved strip, said switch being normally closed when said plunger is depressed and open when said plunger is extended, and a fragile stiff sheet extended across said window and engaging in said grooves for holding said lever and said plunger depressed, said box having an open front side closed by means of a pivotally mounted cover, and said window opening being formed in said cover, said lever being provided upon its 25 free outer edge with a downwardly extending leaf engaging the front face of said cover and maintaining said cover in a closed position until such time as said fragile sheet is broken.

4. Any device of the type described, a box having a window opening, a grooved strip mounted along one side of said window opening, a pivotally mounted lever within said box and extended to the other side of said window opening and having a groove opposed to said groove, a switch for controlling an electric circuit and having a plunger resiliently urged outwards and engaging and urging said lever towards said grooved strip, said switch being normally closed when said plunger is depressed and open when said plunger is extended, and a fragile stiff sheet extended across the window and engaging in said grooves for holding said lever and said plunger depressed, said switch being mounted upon and within said box, said plunger being extended upwards through an opening formed in said wall.

5. Any device of the type described, a box having a window opening, a grooved strip mounted along one side of said window opening, a pivotally mounted lever within said box and extended to the other side of said window opening and having a groove opposed to said groove, a switch for controlling an electric circuit and having a plunger resiliently urged outwards and engaging and urging said lever towards said grooved strip, said switch being normally closed when

said plunger is depressed and open when said plunger is extended, and a fragile stiff sheet extended across the window and engaging in said grooves for holding said lever and said plunger depressed, said fragile stiff sheet comprising a pane of relatively thin glass.

6. Any device of the type described, a box having a window opening, a grooved strip mounted along one side of said window opening, a pivotally mounted lever within said box and extended to the other side of said window opening and having a groove opposed to said groove, a switch for controlling an electric circuit and having a plunger resiliently urged outwards and engaging and urging said lever towards said grooved strip, said switch being normally closed when said plunger is depressed and open when said plunger is extended, and a fragile stiff sheet extended across said window and engaging in said grooves for holding said lever and said plunger depressed,

said box being formed with louvres for the escape of heated air.

7. Any device of the type described, a box having a window opening, a grooved strip mounted along one side of said window opening, a pivotally mounted lever within said box and extended to the other side of said window opening and having a groove opposed to said groove, a switch for controlling an electric circuit and having a plunger resiliently urged outwards and engaging and urging said lever towards said grooved strip, said switch being normally closed when said plunger is depressed and open when said plunger is extended, and a fragile stiff sheet extended across said window and engaging in said grooves for holding said lever and said plunger depressed, said window opening being provided with flanges for supporting said fragile stiff sheet.

EUGENE VAN DAMME.
